DESIGN FOR A PORTABLE GAS STATION

Eugene E. Johnston, Buffalo, N. Y., assignor to
Tank Car Stations, Inc., Buffalo, N. Y., a cor-
poration of New York

Application October 12, 1936, Serial No. 65,278

Term of patent 14 years

To all whom it may concern:

Be it known that I, Eugene E. Johnston, a citizen of the United States of America, residing in Buffalo, in the county of Erie and State of New York, have invented a certain new, original, and ornamental Design for a Portable Gas Station, of which the following is a specification, reference being had therein to the accompanying drawing, forming a part thereof, in which

Figure 1 is a perspective view of the station,

the side not shown being substantially the same as that illustrated with the exception of the pumps which appear on one side of the structure only, and

Figure 2 is a front elevation.

I claim:

The ornamental design for a portable gas station, substantially as shown and described.

EUGENE E. JOHNSTON.
